BURGLAR ALARM

John A. Wall, East Nashville, Tenn.

Continuation of application Serial No. 687,501,
August 30, 1933. This application August 24,
1937, Serial No. 160,708

6 Claims. (Cl. 200—106)

This invention relates in general to electrical circuit closing devices and more particularly has reference to a burglar alarm system.

This application is a continuation of my application Serial Number 687,501, which was filed in the Patent Office August 30, 1933.

Previous to this time practically all of the available burglar alarm arrangements for actuating visual or audible indicators have required extensive alterations in the conventional wiring where it has been desired to install a device in an ordinary circuit. The prior systems have also usually been complex in construction and delicate in operation, so as not to be suitable for installation in a small dwelling or place of business.

An object of this invention is to provide a burglar alarm which may be readily installed in an ordinary light circuit embodying a positive heavy duty circuit closing arrangement actuated to a simple relay.

Another object of this invention is to provide a burglar alarm device simple and compact in construction which may be economically produced and readily installed in an ordinary light circuit.

A further object of this invention is to provide a burglar alarm device which may be readily, positively and simply set in operative position.

A still further object of this invention is to provide a burglar alarm device which may be readily and permanently installed in an ordinary light circuit and embodying an audible as well as a visual indicator, which will not interfere with the normal operation of the light circuit.

With these and other objects in view, which may be incident to my improvements, the invention consists in the parts and combinations to be hereinafter set forth and claimed, with the understanding that the several necessary elements comprising my invention may be varied in construction, proportion and arrangement, without departing from the spirit and scope of the appended claims.

In order to make my invention more clearly understood I have shown in the accompanying drawings means for carrying the same into practical effect without limiting the improvements in their useful applications to the particular constructions which, for the purpose of explanation, have been made the subject of illustration.

In the drawing forming a part of this specification, Fig. 1 is a side view of my burglar alarm

device shown enclosed in a container, the elements set in inoperative position.

Fig. 2 is a side view of the device with the elements shown in operative position.

Fig. 3 is a top view of the device taken on line 5—3 of Fig. 1.

Fig. 4 is a diagrammatic view of the device showing the relation of the elements in an electrical circuit.

Referring more particularly by numerals to the drawings, in which the same and similar elements are designated by like symbols of reference throughout, and more especially to Fig. 1, my novel burglar alarm device comprises a single throw double pole switch embodying a base 15 and blades 2 and 3, as shown in Fig. 3. The blades 2 and 3 are pivoted at one end to ears 4 and 5 mounted on the base 1 and are adapted to selectively engage contacts 6 and 7 mounted on the other end of the base 1. The base 1 of the switch is angularly mounted on an arm 8 formed on the top of a bracket support 9. The bottom of the bracket 9 is formed with flange 10 for securing on an insulator base 11 formed of any suitable non-conductive material, such as fiber. The insulator base 11 is adapted to fit in the bottom of a container 12 for enclosing the elements of the device.

An insulator bar 13 is connected across the ends of the switch blades 2 and 3 and a trigger 14 is centrally fixed on the outer face thereof in longitudinal alignment with the switch blades. The switch blades are normally adapted to be pulled in engagement with the contacts 6 and 7 by a helical spring 15 connected between the trigger 14 and eye 16 fixed on the insulator base 11, as shown in Fig. 2.

A pair of solenoid coils 17 and 18 are positioned opposite the switch, mounted on an upright 19 by an angle iron 20. The upright 19 is fixed on the insulator base 11 by angle irons 21 and 22. An armature 23 is adapted to engage the poles of the solenoids when the coils are energized. The armature is mounted in an upright position on a leaf spring 24 fixed on the upright 19 by an angle iron 25. The armature 23 is normally held out of contact with the poles of the coils by the tension of the spring 24 and is adapted to be engaged at the top by the trigger 14 to hold the switch blades out of engagement with the contacts 6 and 7 against the tension of the helical spring 15. A stop 26 is fixed on the underside of the trigger 14 to position the armature with respect thereto. It will be apparent that with this arrangement of the switch

and relay the blades will be released and pulled into engagement with the contacts 6 and 7 by the tension of the helical spring 15 when the solenoid coils are energized and the armature 23 engaged therewith to release the trigger 14.

An upright 27 is also mounted on the insulator base 11 between the switch and the solenoid coils. The upright 27 is formed with a flange 28 at the bottom for securing on the base, and a flange 29 at the top for extending over the trigger 14 and adapted to act as a stop therefor at its raised position. The bent leaf spring 30 is fixed on the flange 29 for engaging a blade 2 of the switch to complete an electrical circuit between that blade and the upright, as will later be described.

A wire 31 is connected at its lower end to the trigger 14 and extends through aligned apertures provided in the flange 29 and top of the casing 12 and formed with a loop 32 at the top to provide for setting the elements of the device in inoperative position from outside the container. When the switch blades are in engagement with the contacts, as shown in Fig. 2, so that the elements are in operative position, the device may be set by pulling the wire 31 from without the container to bring the armature 23 under the end of the trigger 14 against the stop 28 and the switch blade 2 into contact with the spring 30, where the trigger will be held until energization of the coils, which will withdraw the support of the armature and cause the switch blades to be snapped into engagement with the contacts 6 and 7 by the action of the spring 15. A pair of rivets 33 and 34 are affixed on the armature to engage the poles of the coils and prevent the armature from sticking.

The device is adapted to be interposed in an ordinary electric light circuit for actuating the lights and/or an audible alarm. The coils 17 and 18 may be energized by a dry battery or by transformer currents flowing through the light circuit. In Fig. 4 there is shown a diagrammatic view of the circuit for installing the device in which the numerals 35 and 36 indicate the positive and negative leads of an ordinary light current circuit. The transformer is shown connected across these leads comprising the usual primary and secondary coils 37 and 38 and a core 39. The numerals 40 and 41 indicate leads to conventional circuit closers at all openings, such as windows and doors, which are adapted to be connected in parallel in this circuit. The lead 41 is connected to a terminal comprising a post 42 and nut 43 mounted on the base. There is also connected to the post 42 a lead 44 to the coil 17, which is connected to the coil 18 by a conductor 45. The coil 18 is connected to the upright 27 which is composed of conductive material by an insulated wire 46.

The other lead 40 to the circuit closers is connected to a binding post 47 which also has connected thereto a lead 48 from the transformer and a lead 49 to an audible indicator or bell 50. A switch 51 is interposed in the lead 49 for only selective actuation of the bell. A lead 52 is connected between the audible alarm and a binding post 53, which is also connected to the switch contact 6 by a lead 54. The blade 2 of the switch set in inoperative position is in contact with the leaf spring 30 fixed on the conductor upright 27. Another lead 55 from the transformer is connected to a binding post 56 to which there is also connected a lead 57 to the ear 4, on which the switch blade 2 is pivoted. The switch

contact 7 is connected by lead 58 to a binding post 59 to which there is also connected the line 36 of the light circuit. The ear 4 to which the switch blade 3 is pivoted is connected by a lead 60 to a binding post 61, to which there is also connected one lead 62 from the house lighting current.

The operation of my novel burglar alarm device will be readily apparent from the foregoing description. The device is adapted to be interposed in a light circuit, as described, in series with the master switch in the circuit which is closed for operation of my device, and the light circuit open by setting of the trigger 14 on the armature 23 out of contact with the coils 17 and 18, as shown in Fig. 1 and in the manner described. Where use of the light circuit without operation of my novel device is desired the switch blades are allowed to be pulled in engagement with the contacts 6 and 7, as shown in Fig. 2, and the switch 51 in the bell circuit is open so that the audible alarm will not be actuated.

When operation of my device is desired the trigger 14 is set, as shown in Fig. 1, by raising the wire 31. Whatever lights it may be desired to actuate with operation of the device are left in circuit with the lighting system. The switch 51 in the bell circuit is closed for actuation of the audible alarm, which may consist of a motor to actuate a siren. In the case of banks, a circuit closer, such as a button for being pressed by foot, may be employed. When any one of the circuit closers which are arranged in parallel are actuated, for example by the opening of a window or door to which the same are attached, the coils 17 and 18 are energized by a circuit being closed through the lead 41 to 44, coil 17, conductor 45, coil 18, lead 46, upright conductor 27, conductor spring 30, switch blade 2, leads 57, 55 and 40. The energization of the coils 17 and 18 will draw the armature 23 into contact with the cores thereof, releasing the trigger 14 which will be drawn downward under the tension of the spiral spring 15, opening the aforesaid circuit by the switch blade 2 being drawn out of contact with the spring 30, and closing the bell and house lighting circuit to provide for visible and audible alarms by the switch blades 2 and 3 snapping into engagement with the contacts 6 and 7. The bell circuit is thus closed through leads 52, 54, switch blade 2, leads 57, 55, 49 and switch 51. The light circuit is thus closed to actuate the lights in the circuit through the leads 62, 60, switch blade 3 and leads 58 and 36. If an audible alarm is not desired, switch 51 may be left open. The operation of the device may be discontinued by resetting through lifting of the wire 31 to bring the armature 23 under the trigger 14 and the switch blade 2 in contact with the spring 30, or by opening the master switch in the lighting circuit.

There is accomplished by this invention a burglar alarm device simple in operation, compact in construction and economical of production for connection in an ordinary lighting circuit without substantial alteration thereof for use with or without a battery which will operate to afford a visible, or visible and audible, alarm by the closing of the circuit in which it is connected, such as by the opening of a door or window.

While I have shown and described the preferred embodiment of my invention, I wish it to be understood that I do not confine myself to

the precise details of construction herein set forth, by way of illustration, as it is apparent that many changes and variations may be made therein by those skilled in the art, without departing from the spirit of the invention, or exceeding the scope of the appended claims.

I claim:

1. In a switch construction, a casing, a pair of contact members mounted within the casing, a pair of blade members adapted to engage said contacts, a trigger movable with and in longitudinal alignment with said blades, a spring secured to the trigger and the base of the casing for normally urging the blade members into engagement with the contacts, a stop member mounted on the base of the casing for limiting the upward movement of the trigger, a spring contact mounted on the stop member for contacting one of the blade members, when the trigger is moved to its uppermost position, and a spring supported element provided on the base of the casing for holding the blade members out of engagement with the contacts.

2. In a switch member, a casing, an angularly arranged support member, a pair of contacts carried by said support, a pair of blade members pivotally secured to said support and adapted to engage said contacts, a trigger movable with and in longitudinal alignment with said blades, a spring secured to the trigger and the base of the casing, for normally urging the blades into engagement with the contacts, a stop member mounted within the casing for limiting the upward movement of the trigger, and a spring supported element provided on the base of the casing for contacting said trigger for holding the blade members out of engagement with the contacts.

3. In a switch member, a casing, an angularly arranged support member, a pair of contacts carried by said support, a pair of blade members pivotally secured to said support and adapted to engage said contacts, an insulating strap connecting the blade members, a trigger attached to the insulating strap, movable with, and in longitudinal alignment with said blades, a spring secured to the trigger and the base of the casing, for normally urging the blades into engagement with the contacts, a stop member mounted within the casing for limiting the upward movement of the trigger, and a spring supported element provided on the base of the casing for contacting said trigger for holding the blade members out of engagement with the contacts.

4. In a switch member, a casing, an angularly arranged support member, a pair of contacts

carried by said support, a pair of blade members pivotally secured to said support and adapted to engage said contacts, a trigger movable with, and in longitudinal alignment with said blades, a spring secured to the trigger and the base of the casing for normally urging the blades into engagement with the contacts, a stop member mounted within the casing for limiting the upward movement of the trigger, a spring supported element provided on the base of the casing for contacting said trigger for holding the blade members out of engagement with the contacts, and a flexible member connected with the trigger and extending through the top of the casing, to move the trigger into contact with the spring supported element.

5. In a switch member, a casing, an angularly arranged support member, a pair of contacts carried by said support, a pair of blade members pivotally secured to said support and adapted to engage said contacts, an insulating strap connecting the blade members, a trigger attached to the insulating strap, movable with, and in longitudinal alignment with said blades, a spring secured to the trigger and the base of the casing, for normally urging the blades into engagement with the contacts, a stop member mounted within the casing for limiting the upward movement of the trigger, a spring supported element provided on the base of the casing for contacting said trigger for holding the blade members out of engagement with the contacts, and a flexible member connected with the trigger and extending through the top of the casing to move the trigger into contact with the spring supported element.

6. In a switch member, a casing, an angularly arranged support member, a pair of spring contacts carried by said support, a pair of blade members pivotally secured to said support, and adapted to engage said contacts, an insulating strap connecting the blade members, a trigger attached to the insulating strap, movable with, and in longitudinal alignment with said blades, a spring secured to the trigger and the base of the casing, for normally urging the blades into engagement with the contacts, a stop member mounted within the casing for limiting the upward movement of the trigger, a spring supported element provided on the base of the casing for contacting said trigger for holding the blade members out of engagement with the contacts, and a flexible member connected with the trigger and extending through the top of the casing to move the trigger into contact with the spring supported element.

JOHN A. WALL.
